United States Patent

Des. 234,296
Patented Feb. 11, 1975

234,296

BUILDING

Eufrecio Zamora, Conroe, Tex.

Filed Aug. 9, 1973, Ser. No. 386,966

Term of patent 14 years

Int. Cl. D25—03

U.S. Cl. D13—1 B

FIG.-1

FIG.-2

FIG.-3

FIG. 1 is a front perspective view of the building design of this invention taken from above the building;

FIG. 2 is another front perspective view of the building design of FIG. 1 as seen from ground level; and

FIG. 3 is a back view of the building of FIG. 1.

I claim:

The ornamental design for a building, substantially as shown and described.
